UNITED STATES PATENT OFFICE

2,113,613

MULTIPLE PANED WINDOW

Frank W. Daemicke, Chicago, Ill., assignor to The
Daemicke Company, Chicago, Ill., a corporation
of Illinois

Application March 13, 1936, Serial No. 68,695

6 Claims. (Cl. 20—56.5)

My invention, although applicable to use wherever double or multiple glass panels are feasible, is especially adapted to display cases or service counters and particularly of the refrigerated type for displaying perishable articles of food, such as meats and the like; the side and end walls involving glass panels in order that the merchandise may be properly visible, the glass panels in these display cases being preferably substantially coextensive with the upper part of the case above the food holding rack or inner bottom portion of the merchandise holding part of the case.

In display cases of the type in question the rear side of the case consists of slidably mounted glass panels or sliding doors whereby access by the salesman to the displayed articles is possible. These sliding doors frequently are provided with spaced apart, parallelly arranged glass panels in order to prevent the too rapid transfer of temperature or warming up of the case interior.

In view of the difficulties of hazing or fogging heretofore encountered, double or multiple glass panels are not generally used at the front side of the case or counter because the condition encountered interfered with the customers' visibility and hence single glass panels, that are accessible from both sides, have generally been employed with the result that great temperature losses have been encountered.

The object of my invention is to overcome the difficulties heretofore encountered and to provide a window construction, whether as the show window of a store or as a display case of the character mentioned, involving a multiple of glass panes or panels arranged in spaced relation and each panel thoroughly sealed in the window frame or main frame portion of the display case against ingress of air and moisture and an hermetically sealed air chamber or chambers between the glass panels provided, thereby eliminating all possibility of condensation and the formation of a haze or fog on the glass; the spaced glass panels with intervening hermetically sealed spaces maintaining the desired temperature in the windowed compartment or display case interior and preventing condensation on the inner and opposing sides of the respective glass panels.

The objects and advantages of my invention will be more readily understood from the detailed description of the accompanying drawing which, for purposes of exemplification, show the invention applied to a well known type of display case, wherein:

Figure 1 is a perspective sectional view of a display case involving my invention.

Figure 2 is a cross sectional view taken substantially on the line 2—2 of Figure 1.

Figure 3 is a cross-sectional view taken on the line 3—3 of Figure 2.

Figure 4 is an enlarged perspective view of a

section of the spacer strips employed in Figures 1 and 2.

Figure 5 is a similar view showing a modified form of spacer strip.

My invention, which relates to a multiple paned window regardless of the nature of the window containing structure, is especially adapted to refrigerated display cases—whether mechanically or otherwise refrigerated—of the type intended for displaying meats and other perishable food-stuffs, and in order to illustrate the invention and its method of construction, its application to a well known type of display counter is disclosed in the drawing, wherein a portion of a slideable door at the rear or salesman's side of the display case is shown at 10 in Figure 1; these slideable doors or panels being mounted so that one panel or section will lap the other when slid out of normal or closed position.

The invention and its application is more easily disclosed in connection with the forward side of the case and the description will, therefore, be confined to this part of the case.

In order to prevent the conduction of the warmer or room temperature and to maintain the desired low temperature within the display case, a plurality of spaced apart glass panels 11, for illustration three in number, are provided on the forward or customers' side of the display case as shown in Figure 1. These glass panels are spaced sufficient distances apart and preferably in parallel relation as shown to provide intervening hermetically sealed air insulating spaces therebetween to prevent the transfer of the warmer exterior temperature to the case interior.

In order to permit the use of a plurality of glass panels as mentioned it is essential that the respective panels be hermetically sealed in the frame against ingress of air and moisture; the use and proper installation of multiple glass panels enabling a low temperature to be maintained without producing condensation on the inner sides of the glass panels.

In the particular exemplification of display case, top sections 12, 12 are shown preferably with suitable insulation 13 therebetween, while the forward side of the case is provided with the rectangular frame 14 snugly joined to the top, side and front walls of the case.

The frame is preferably chamfered on the inner perimeter as shown at 15 to receive the inner glass receiving frame members 16 which are also suitably grooved or chamfered as shown at 17; the chamfer extending to the outer edge of the frame members 16 at one side, while the side wall 55 at the other side of the chamfer is preferably slightly undercut or beveled as shown at 18 in Figure 2. It will be understood that the frame members 16 extend about the four sides of the opening in the structure or case and that the 60

chamfers of the respective members 16 correspond and connect with each other in order that the four marginal edges of the rectangular glass panels may extend somewhat into the respective 5 chamfers as more clearly shown in Figure 2.

The frame members in the illustration are of width sufficient to properly receive a plurality of spaced glass panels 11, for example three in number as shown; the glass panels being preferably 10 equally spaced apart and the intermediate panel maintained in spaced relation with the two side panels 11 by means of the spacing strips 19, 19, which extend throughout the length of the chamfers and along the four marginal edges of the 15 glass.

These spacing strips are kerfed along the opposite longitudinal sides to receive a longitudinal marginal portion of the rubber strips 20, 20, which extend continuously throughout the length of the 20 strips 19 and are preferably glued or otherwise firmly secured in the kerfs.

The kerfs with the inserted rubber strips are preferably arranged a slight distance removed from the flat face sides of the strips 19, see Figure 2. This face side of the spacing strips is preferably covered with a strip of channel shaped sheet metal as at 21; the rubber strips, however, extend somewhat beyond the plane of the sides of the metal channel 21.

30 The two longitudinal sides of the spacing strips between the kerfs and the base sides 22 of the strips are inwardly tapered or sloped as shown at 23 to provide recesses; while the base portions of the strips are laterally extended as shown at 35 24, 24; these base portions or flanges being made to extend somewhat beyond the plane of the kerfed sides of the strips, as more clearly shown in Figure 4.

40 These extended base portions 24, 24 are intended to lap and rest on the edges of the glass panels as shown in Figures 1 and 2, while the rubber strips 20, 20 are intended to be in snug relation with the sides of the glass panels. It is apparent that during assembly of the structure the 45 spacer strips 19 will be held in position in the channel of the frame member by the glass panels and hence displacement of the spacer strips is impossible.

50 The glass contacting faces of the base portions 24, 24 are undulated or serrated as shown at 25 in Figure 4 in order to permit the sealing compound shown at 26 to flow from the main portion of the chamfer 17 into the recesses between the tapered sides of the spacing strips 55 and the sides of the glass panels.

55 The flow of the sealing compound out of the recesses mentioned is prevented by the rubber strips 20; the snug relation between the rubber strips 20 and the sides of the glass panel preventing the seepage of the compound along the sides of the glass beyond the spacing strips.

In order also to maintain the spacing strips 19 in spaced relation with the bottom of the 60 chamfer 17 in the frame and to enable the sealing compound to flow from side to side of the chamfer and completely around the three sides of the spacing strips 19, I prefer to provide the bottom of the chamfer or groove 17 with narrow strips 27 disposed transversely of the spacing strips 19; the strips 27 being preferably secured 70 to the grooved frame member 16 and of length less than the width of the chamfer so as to allow flow of the sealing compound about the ends of the strips 27.

75 The sealing compound 26, preferably asphalt,

may be introduced through the open side of chamfer 17 after the glass panels and spacing strips have been put into place; the side wall 18 of the chamfer having been previously provided with a sealing or rubber strip as at 28, see Figure 2, adapted to provide snug relation with the side of the adjacent glass panel and prevent seepage of the sealing compound on the inside face of the inner glass panel. As previously stated, asphalt is preferably used as the juncture providing 10 or sealing compound, although any other solidifying and yet elastic compound may be employed, namely a compound which may liquefy sufficiently to be poured into the chamfer and which will seep through the serrations into the recesses 15 between the spacing strips and the glass and which at the same time will properly and sufficiently solidify so as not to flow and yet remain in a more or less plastic or elastic state so as to 20 constantly maintain intimate relation with the glass panels and with the spacing strips and the frame members and hence provide a definite airtight seal against air and moisture.

Construction of my improved hermetically sealed structure is preferably performed in dehydrated atmosphere, namely in a room in which the air has been dehydrated and the sealing compound applied to the glass holding portion of the frame members before the window or display case is assembled, thus enabling the chamfers in the frame members to be so positioned that the compound may be poured and caused to flow toward the closed side of the chamfer and about the glass panels and spacing strips as heretofore mentioned.

30 After a sufficient quantity of the sealing compound has been introduced and partially set, the open side or end of the chamfer 17 is then provided with the finish strip 29, which may be held in place by suitable screws as at 30 in Figure 2; 40 the finish strip 29 being put into place after the compound has been poured and has partially set, thus allowing for slight shrinkage or contraction in the compound; a slight amount being added if shrinkage or contraction beyond a certain degree has taken place.

45 In Figure 5 I illustrate a slight modification of spacing element or strip 31, which in general cross-sectional configuration is similar to the spacing strip 19; strip 31 differing in that, instead of having the longitudinal kerfs for reception of the rubber strips 20, the rubber strips 32 are glued or otherwise securely fastened along the longitudinal sides of the spacing strips 31 as shown so as to make a snug, sealing contact 50 with the sides of the glass panels and thus prevent egress of the sealing compound while the latter is in a more or less fluid state during assembly.

55 The spacing strip 31, like the spacing strips 60 19, require no screws or nails to hold them in place, and hence there are no holes or crevices in the strips, because the lateral base extensions lap the edges of the glass panels and are thereby held in place as well as by the sealing compound 65 after the latter has been poured and solidified; warping of the spacing strips or pulling away from the sealing compound or out of contact with the glass being impossible.

60 The spacing strip 31 may also be provided with an outer metallic covering like that shown at 21 in Figure 4, or the entire spacing strips may be made of metal instead of wood as shown, as may also the frame members 16.

75 With the crevices and recesses about the edges

of the glass panels and the spacing strips completely filled with the plastic or elastic sealing compound it is apparent that a low temperature in the display case can be readily maintained in view of the non-conducting sealed chambers or spaces between the inner and outer glass panels and the intermediate panel; a definite air-tight seal being provided against moisture. As previously stated, the assembly of my improved display case is preferably performed in a dehydrated atmosphere and hence the formation of a haze is impossible and the possibility of fogging of the glass is eliminated.

While my invention is especially adapted to the type of display case herein defined and as shown in the drawing, it is apparent that the improvement is equally adapted for use in connection with any type of windowed compartment or chamber where visibility or admission of light is desirable and I, therefore, do not wish to be understood as limiting myself to the exact type and style of construction disclosed but rather to the invention as defined in the appended claims.

25. What I claim is:—

1. A multi-paned window of the character described comprising a main frame the inner perimeter whereof is provided with a channel open at one side of the frame; a plurality of glass panels for said frame arranged with the marginal edges extending into said channel on the inner perimeter of the frame; spacing strips intermediate of the glass panels adapted to hold the latter in spaced relation, the longitudinal sides of the strips being recessed away from the panels while the outer longitudinal edges of the strips are adapted to contact the sides of the glass panels, the inner or base portions of the strips being laterally extended to overlap the edges of the glass panels, said extended portions being provided with transverse valleys or kerfs for establishing communication between the recesses at the sides of the strips and the channel in the frame; a solidifying plastic compound in the channel and a finish strip for closing the open side of the channel.

2. A multi-paned window of the character described comprising a window frame formed to provide a continuous channel about the inner perimeter of the frame; a plurality of spaced apart glass panels arranged in the frame with their edges extending into the channel without contacting the bottom of the channel; spacing strips arranged in the channel intermediate of the glass panels and having base portions which overlap the edges of the panels and thereby effect supporting relation with the glass panels, said base portions being provided with interrupted glass contacting surfaces, while the sides of the strips have sealing compound receiving recesses communicating with the channel about the edges of the panels across said interrupted surfaces; yielding means adjacent the outer edges of the spacing strips and adapted to engage the sides of the panels whereby flow of the sealing compound out of the channel and the recesses is prevented; means for holding said spacing strips in spaced relation with the bottom of the channel; and a plastic sealing compound filling said channel and the recesses whereby the glass panels are hermetically sealed against ingress of air and moisture.

3. A multi-paned window of the character described comprising a frame formed to provide a continuous channel about the inner perimeter,

a plurality of glass panels whose marginal edges extend into said channel without seating in the bottom of the channel; spacing means arranged in said channel intermediate of adjacent glass panels and provided with laterally extended base portions adapted to overlap the edges of the glass panels and to be thereby held in place, the extended base portions and sides of said spacing means having connecting recesses arranged in communication with said channel; the channel in the frame and said recesses being filled with a plastic air drying sealing compound; and resilient sealing means disposed intermediate of said spacing means and the sides of the glass panels and intermediate of the side wall of the channel and the adjacent glass panel for preventing outflow of the sealing compound.

4. A multi-paned window of the character described comprising a frame formed to provide a continuous channel on its inner perimeter open at one side; a plurality of glass panels with their marginal edges extending into said channel; means for holding the glass panels in spaced relation with each other and arranged in said channel so as to provide spaces in the channel about said means, said means being adapted to effect sealing relation with the sides of the glass panels adjacent the outer faces of said means while providing sealing compound receiving spaces about the edges and marginal sides of the panels; a plastic sealing compound in said spaces provided by said first mentioned means and a closure strip for the open side of said channel.

5. A multi-paned window of the character described comprising a frame adapted to extend continuously about a sight-opening and having a continuous channel about said opening; a plurality of glass panels for said opening with the marginal edges of each panel extending into said channel; spacing elements disposed intermediate of the glass panels to hold the latter in spaced relation, both longitudinal sides of each element being tapered toward the base while the sides adjacent the outer faces of each element are adapted to lap the sides of the glass panels, the base of each element being extended laterally beyond opposite sides and said extensions to overlap the edges of adjacent glass panels, said laterally extended base portions being formed to establish communication between the recesses at the tapered sides of the spacing elements and the channel in the frame; and a solidifying sealing compound in said channel about the bases of the spacing elements and about the tapered sides of said elements whereby ingress of air and moisture between the glass panels is prevented.

6. A multi-paned window of the character described comprising a frame formed to provide a continuous channel on its inner perimeter and open on one side; a plurality of glass panels with their marginal edges extending into said channel; means for holding the glass panels in spaced relation with each other, said means having holding relation with the sides and the edges of the panels and being arranged in spaced relation with the bottom of the channel to provide a communicating passage through the channel beneath said means and about the side edges of the panels; a plastic sealing compound in said communicating passage; means whereby flow of said compound along the sides of the glass panels is prevented; and means for closing said open side of the channel.
